UNITED STATES PATENT OFFICE.

MARIE W. MERRILL, OF NEW YORK, N. Y.

ORNAMENTAL CARD OR SHEET.

1,121,858.

Specification of Letters Patent. Patented Dec. 22, 1914.

Application filed August 18, 1913. Serial No. 785,356.

To all whom it may concern:

Be it known that I, MARIE W. MERRILL, a citizen of the United States, and a resident of the borough of Brooklyn, city and State of New York, have invented certain new and useful Improvements in Ornamental Cards or Sheets, of which the following is a specification.

This invention has most particular reference to an ornamental card or sheet, which may be used separately, or made to form the front face of a container preferably made of paper and having a pocket or receptacle for containing sachet powder, or other articles, such for example, as separate announcement, anniversary or commemorative cards; the object being to provide a device of the kind stated which will be of most striking appearance, preferably of highly artistic character, and which at the same time may be inexpensively produced, thereby affording a most pleasing and inexpensive device for gift or other purposes. This purpose, and others which will appear from the following description of the invention, are well subserved by the construction illustrated in the accompanying drawings to exemplify the invention, but to the details of which the invention is not restricted, as many changes may be made in the exemplified embodiment without departing from the spirit of the invention, or the scope of the subjoined claims.

In said drawings: Figure 1 is a front view of a container constructed in accordance with the present invention with a corner of the front layer turned back to show a suitable way of securing the same to the adjacent layer; Fig. 2 is a rear view of the front layer thereof; Fig. 3 is a rear view of the container; Fig. 4 is a section on the line 4—4 of Fig. 3; Fig. 5 is a section through the front layer, on the line 5—5 of Fig. 1; Fig. 6 is a front view of a modified form; Fig. 7 is a perspective view of said modified form with the front layer removed.

Similar characters of reference denote corresponding parts in the several views.

Referring now to the form of the invention exemplified by Figs. 1—5 inclusive, of the drawings, it will be noted that the device comprises three layers, marked A, B and C respectively, and that the part comprising the layers B and C is of substantially the form of an envelop, the layer B having reverted transverse and longitudinal portions which form the layer C, said re-

verted transverse portions forming end flaps 10 and 11 whose ends overlap each other and said reverted longitudinal portions forming upper and lower flaps 13 and 14 whose ends overlap the flaps 10 and 11 and whose longitudinal free edges overlap each other, as shown by the dotted lines in Fig. 3. A pocket between the layers B and C is thus formed, and this pocket is shown as containing a pad D holding sachet powder. For this particular use there is no special need of affording provision for access to the pad without tearing or destroying the container, but when the device is embodied as a means for holding a remembrance card, for example, it may be preferred to correlate the layers B and C so that access to the pocket between them may be had without mutilating or destroying the device. Such access to the pocket may be provided for in various ways of more or less obvious kind, one simple and obvious way being the use of an envelop having an end flap which can be opened. It will, accordingly, be understood that the present invention is not limited to a device having a container portion of a kind which cannot be readily opened, or opened without destroying or mutilating the same, or indeed to any particular construction of container. It should be understood in this connection that the container portion of the device is provided with means, hereinafter described in detail, which form a part of the means for giving the device a pleasing appearance, and that this means extends through both of the layers and is so arranged that it cannot conveniently be detached and replaced. Hence, when access to the interior of the pocket without mutilating or destroying any part of the container, is to be afforded, it is preferred that provision for this be made by so correlating the parts that an end of the container can be conveniently opened and closed without disturbing the means, hereinbefore referred to, which extend through the layers B and C, the pocket being in this, as in the exemplified form of the invention, provided between the said means and the upper or lower edge of the container. While only one such pocket has been referred to it will be apparent that two such pockets may be provided, and, in fact, two are shown, although only one is utilized, in the exemplified form of the invention, these pockets being divided from each other

at the place where the hereinbefore referred to means which extend through the layers are located. Accordingly, it will be obvious that if desirable provision for convenient access 5 to both of said pockets, without mutilating the container or disturbing the said means, may be made.

The front layer A has impressed thereon, either plain, or in intaglio or relieve, but 10 preferably plain, a picture E or other ornament, the material of the layer being interrupted at suitable intervals within the picture, and a material or materials of a kind appropriate to the picture and having ends 15 which are confined at the rear of the layer A, extends through the spaced apertures and completes the representation. This representation is preferably of an ornamental nature, but may be of any suitable character, 20 its striking and pleasing character being of course accentuated by being composed in part of an impression and in part of an exposed material appropriate to the design and which material is suitably secured at 25 the back of the layer A and covered by the next adjacent layer of the device.

The way in which the impression and material are combined and correlated to form the representation, picture, or design, forms 30 one of the severally new and important features of the present invention, and this is well exemplified in the accompanying drawings wherein the front layer is shown as containing an ornamental representation of 35 a girl's head, neck and chest, together with the upper part of a gown having a low-cut neck. The hair is provided with a bandeau, this bandeau being in part printed and in part formed of a ribbon or ribbons, the 40 latter being selected because it is the material of which bandeaux are ordinarily formed in practice and forming, as will be hereinafter more clearly seen, puffed and bowed parts of the bandeaux. The bandeau 45 is represented as having smooth portions 15 alternating with puffs 16 and terminating in loops 18 and 19, forming a bow, the said bow having a loose end 22. The smooth portions 15 of the representation are the printed, 50 ed parts thereof, the puffs 16 are, as stated, formed of ribbon and these extend through suitably spaced openings 17 which are formed in the layer A and interrupt or lie within the printed representation of the 55 bandeau, transversely of the latter. The bow, also made of ribbon, is a false bow in that it is not actually tied but is formed of properly spaced loops 18 and 19, respectively, extending through apertures 21 and 60 20 formed in the layer A, while the loose end 22, also extends through an aperture 23.

Two pieces of ribbon are preferably employed in the ribbon part of the bandeau, as 65 shown most clearly in Fig. 2. In the latter figure one of said pieces is marked A¹⁶ and

the other A¹⁸. As will be seen upon reference to Figs. 1, 2 and 5, the piece A¹⁶ extends diagonally across a part of the rear face of the layer A and one of its ends, a¹⁶, is pasted or otherwise suitably secured to said layer. 70 Its other end is looped through the aperture 20 to form the bow-element 19, while the intermediate part of the ribbon is puffed transversely at suitable intervals, these puffs extending through the aperture 17 and 75 forming the bandeau-puffs 16. The other piece of ribbon, A¹⁸, is looped to form the bow-element 18, and has one of its ends at the rear end of the card, while its other end extends from the rear through the aperture 30 23 to form the loose bow-end 22. The size of the apertures through which the exposed portions of the puffs of ribbon extend are preferably such, with relation to the puffed and looped portions of said ribbon, as to render it unnecessary to rely upon any other fastening means at these places and the loops and puffs overlie the apertures at the front and conceal the same, thus simplifying the structure and adding to the pleasing appearance afforded by the representation. 90

In the herein exemplified form of the invention, the neck portion of the dress is pictorially represented, as shown at 25, but the layer A along the edge of said representation is interrupted by apertures 26 and 27, through which a piece of ribbon A²⁸ is run in and out in a manner such as to have two separated exposed parts 28 arranged to give the effect of an edging to the neck of the 100 dress. This is provided for, as most clearly shown in Fig. 2, by forming the ribbon with longitudinally extending spaced puffs at the places marked a²⁸ in said figure.

The picture is completed by a third ribbon, marked A³⁰, in Fig. 2, looped between its ends to form a puff 30 which extends through an aperture 29 and covers the same at the front. One or both ends of the ribbon A³⁰ extends through an aperture or apertures to the front of the card. There is thus provided at this place a bow decorating the representation of the dress. In the exemplification, one end (31) only is shown as being exposed at the front, the other end, 32, being disposed at the back of the layer. The exposed portions of the ribbons A²⁸ and A³⁰ conceal the openings through which they extend and said openings are preferably of such size that, together with the drawing in 110 of the ribbons adjacent to the puffs or loops, as to make it unnecessary to resort to additional means of securing the ribbons to the layer A, but obviously such additional means 120 may be employed without departing from the spirit of the invention.

The portions of the ribbons which are arranged at the back of the layer A are concealed and protected by the layer B and said layers are suitably secured together along 130

their contacting edges, as indicated at 35 in Fig. 1, by pasting or otherwise.

The back layer C, formed in the present exemplification of the invention by the flaps 10, 11, 12 and 13, has its exposed surfaces provided with ribbon arranged to give the effect of a double bow with exposed ends. Two pieces of ribbon are preferably employed in making this double bow, and said 10 pieces of ribbon extend through the layers, serving thereby to tie the layers together and to divide the pockets from each other, as well as to decorate the rear surface of the device. The layers B and C are formed 15 with registering angularly-disposed openings 40, 41, 42 and 43, seen best in Fig. 3. The bow 45 and the exposed end 46 are preferably formed of one piece of ribbon. This piece of ribbon has one end, 47, arranged 20 between the layers A and B, and extends thence through the apertures 40 to the exposed surface of the layer C, where it is looped to make the bow 45, and thence again through the apertures 40 to the forward 25 face of the layer B and thence again rearward, through the apertures 41 to the exposed face of the layer C upon which latter it is prolonged to form the loose end 46. The bow 48 and the exposed end 49 are 30 preferably formed from a separate piece of ribbon, which extends in like manner through the apertures 42 and 43 in the two layers B and C.

It will be noted that the ribbon from 35 which the bows 45 and 48 are formed extends through the several flaps 10, 11, 12 and 13, forming the rear layer C. This, together with the fact that the bow is not a tied one, makes it difficult to open the container part of the device without mutilating 40 the latter: but, as already stated, if it is desired to produce a device having a pocket with provision for convenient access to the interior of said pocket, one or more of the 45 flaps may be arranged to be readily opened and the ribbon, of course, will not extend through such flap or flaps: or, if preferred, the bow may be a tied one, but I prefer the construction set forth. Again, it is obvious 50 that the rear layer C need not be composed of a plurality of flaps as it may, if desired, be made of a single thickness of material, without departing from the spirit of the invention.

55 In Figs. 6 and 7 there is illustrated a form of the invention differing in two respects from that already described. One of these points of difference is in the fact that the layer B is omitted, there being merely an 60 edge or edges, marked B¹⁰, to which the overlying edges of the front layer, marked A¹⁰, is pasted or otherwise suitably secured. Another point of difference is in the fact 65 that the ribbon which forms the edging for the neck of the dress is integral with the

ribbons which extend transversely through the container portion of the device. It will be apparent that either or both of these changed features may be employed. That is to say, the change with respect to the ribbon 70 may be used whether or not the layer B be changed, and that the change with respect to the layer B may be employed without essentially adopting the change relative to the ribbon. When the referred to change 75 with regard to the layer B is adopted it will be apparent that the front of the container is formed by the layer marked A¹⁰ which need not essentially be different from the layer A, hereinbefore described. 80

Referring particularly to Fig. 7 it will be noted that the layer C has four angularly disposed openings, marked 40^a, 41^a, 42^a and 43^a respectively. A single ribbon is illustrated, and this ribbon has both of its ends, 85 marked 46^a and 49^a respectively, exposed to form loose ends of the bow, the intermediate part of the ribbon being arranged to form the bows 45^a and 48^a on the exposed surface of the layer C and the puffs 28^a on the exposed surface of the layer A. Starting with the end 46^a, for example, the ribbon extends forward through the opening 41^a, thence within the space between the layers A¹⁰ and C¹⁰ to the opening 42^a, through the latter to 90 the exposed side of the layer C¹⁰ and thence around and back to said opening 42^a to form the bow 48^a, thence forward through the opening 42^a and around the two separated puffs 28^a corresponding to the puffs 28, 95 thence again back and through the opening 40^a to the exposed side of the layer C¹⁰ and around to form the bow 45^a, thence again through the opening 40^a and across to the opening 43^a, thence through the latter to 100 105 form the loose end 49^a.

The purpose, construction and advantages of the present invention will be readily comprehended from the foregoing description and it will have been noted that the invention may be variously embodied without departing from its spirit or the scope of the subjoined claims, different embodiments having been illustrated and expressly suggested, while others not particularly referred to herein will readily suggest themselves to persons who understand the invention. 110 115

While it is preferred that the invention be embodied in a device having a pocket adapted to constitute a receptacle for some 120 article or articles, yet this is not wholly essential to the invention considered in its broadest aspects and advantage of certain parts of the invention may be received from a structure which does not include a pocket 125 or receptacle as a part of the device.

Having now described the invention what I claim is:

1. A device of the kind set forth having upon a surface thereof a representation of 130

an object which in part is impressed and which in part is formed of fabric appropriate to the representation and provided with spaced openings variously disposed within 5 the said representation, the fabric or sheet material necessary to complete the representation being worked through the said openings into shirrings and loops and frictionally held in place therein in raised position to represent loops or shirrings thereby 10 producing with the material itself the ribbon or trimming effect expressed in the picture or representation.

2. A device of the kind set forth, comprising 15 a plurality of layers, the exposed surface of one of said layers having thereon a representation which in part is formed in fabric appropriate to the representation, the said layer having openings within or adjacent to 20 the pictorial part of the representation and through which the fabric extends from the

rear surface thereof to give a natural effect to the complete pictorial representation of raised shirrings and bows, the parts of the fabric on the rear surface of the layer being 25 concealed and protected by the adjacent layer of the device, the rear layer of the device having a plurality of openings and a fabric extending through said openings from the exposed side of said layer and formed 30 between its ends with loops, the said ends and loops of the fabric being exposed and relatively arranged to give the effect of a tied bow.

In witness whereof I have hereunto set my 35 hand at borough of Brooklyn, county of Kings, and State of New York, this 21st day of July, 1913.

MARIE W. MERRILL.

In presence of—

E. P. MERRILL,
WILLIAM WHITTAKER.
